UNITED STATES PATENT OFFICE.

ANSON N. PALMER, OF SYRACUSE, NEW YORK.

DRIER.

SPECIFICATION forming part of Letters Patent No. 249,978, dated November 22, 1881.
Application filed April 21, 1881. (No model.)

To all whom it may concern:

Be it known that I, ANSON NEWTON PALMER, of Syracuse, Onondaga county, New York, have invented a new and Improved 5 Drier, of which the following is a specification, reference being had to the accompanying drawings, in which—

Figure 1 represents a longitudinal section of the drier complete; Fig. 2, the upper or feed 10 end of the cylinder in elevation; Fig. 3, the lower or discharge end of the cylinder in elevation; Fig. 4, a transverse section of the cylinder, taken on the line $x x$ of Fig. 1; Fig. 5, a detail side elevation of the discharge end of 15 the cylinder, showing a portion of the shell or jacket broken away to expose the water-discharge device; and Fig. 6 is a sectional view, being an enlarged detail, showing the manner in which the joints of the inlet and of the out- 20 let fixed and revolving branches of the steam-pipes are made in the fixed cylinder-heads.

The drawings show the drier attached to and provided with the necessary apparatus and appliances for cutting and drying tobacco; but 25 it can be used for other and general purposes of drying and mixing various substances quickly and uniformly with a minimum of labor, and at the same time purify and improve the substance being dried, both as to quality and flavor. 30 The points of my improvements embrace matters of construction and of combination, which will be specifically made the subject of the claims, in connection with a revolving drier receiving the substance to be dried at one end 35 and discharging it automatically at the other end.

The apparatus is constructed as follows, when applied to the use of drying tobacco:

A is an ordinary tobacco-cutter.

40 B is a suction fan or drum, connected with or attached to the cutter A in any ordinary manner.

C is an air spout or pipe extending from the fan B upward and into the receiver D. This 45 receiver is a box so constructed as to receive the tobacco and allow the air to escape while the tobacco drops into the spout E, which is a feed-spout leading from the bottom of the receiver down and into the head F, and projecting through it a short distance into the cylinder H, which is usually made of boiler-iron,

and is about twenty feet long by three feet in diameter, more or less. It is constructed with two shells, one within the other, and from one and a half to two inches apart all around, of 55 which b is the outer shell, and c the inner one. These shells are made steam-tight, and are connected by a steam-tight joint.

Around both ends of the cylinder, at or near the ends, are the flat rims or bands o. (Shown 60 in Fig. 5.) The head F is made with a flange, d, which fits over the rim o at that end of the cylinder closely, so as to make a tight joint, in which packing can be used, if desired. The head G is made with a similar flange, d, fitting 65 the rim o at that end of the cylinder. The drawings show the shape of this flange d, which fits closely, yet loose enough to allow the cylinder to turn while the heads and flanges are stationary. Both of these heads are supported 70 independently of the cylinder by stay-rods, or in any ordinary manner.

In the lower part of the head G is the discharge-opening f through the face of the head, the flange being whole, as in Fig. 3.

Inwardly-projecting shelves e upon the inside of the cylinder can be used, if desired.

A steam-supply pipe, $h h'$, passes through the head F, extends into the cylinder H a short distance, and, turning down to and through the 80 shell c of the cylinder, opens into the steam-chamber between the shells. By this pipe the cylinder is heated. The steam-outlet pipe $i' i$ extends from the steam-chamber out through the head G, as shown in the drawings. This 85 pipe also carries off all the water created in the steam-chamber by condensation of the steam; and for collecting this water and facilitating its flow into this pipe $i' i$, a rim or plate, y, Fig. 5, is placed between the shells, to fill the space 90 between the shells, and partially circular in shape, which, by the revolution of the cylinder, collects the water within it and carries it up with it until the water runs into the pipe $i' i$, which conducts it away. Both of these 95 pipes $h h'$ and $i' i$ are steam-tight in all their connections; and where they pass through the heads are provided with universal joints or couplings placed in the heads, so that those parts of the pipes inside of the heads revolve 100 with the cylinder, while the rest of the pipes remain stationary; and by this construction

that part of each pipe outside of its head assists in holding each head in place and steady-
ing it.

K is an air-pipe leading from within the cyl-
inder out through the lower part of the head,
F, and extending to a suction-fan, L, to which
it is connected in any ordinary manner, and M
is a discharge-pipe from this fan.

The cylinder H is mounted upon the friction-
rollers l l' in any ordinary manner, and lies
upon them in a somewhat inclined position,
the feed end covered by the head F being the
highest. Bands s are placed around the cyl-
inder upon which the rollers run.

The roller l is made flat or plane upon its
outer or bearing surface, and the roller l' is
made with a flange upon its right-hand edge.

Friction-rollers m, Figs. 2 and 3, with a
flange upon the right-hand edge, are used at
each end of the cylinder, so mounted and lo-
cated as to bear against the bands s at each
end of the cylinder, on opposite sides at or near
the center of it perpendicularly, for the pur-
pose of steadyng it while being revolved.

These flanges on the rollers m fit over the edge
of the band s of the cylinder and prevent the
sliding or endwise movement of the cylinder.
Flanges may also be made on both sides of all
of these friction-rollers, if desired.

R is a suspended shaker-sieve, so located as
to receive the discharge from the cylinder, and
can be used when it is desired to screen the
material being dried. It can be connected
with the mechanism which revolves the cylin-
der in such a manner that it will have a con-
stant vibratory or shaking motion.

The box S is used to catch the material which
passes through the sieve.

The cylinder can be mounted upon a founda-
tion of masonry or timber, or suspended from
above on timber bents, as shown in the draw-
ings.

For drying tobaccos it is operated as follows:
Everything having been set up, as described
and shown in the drawings, and started up,
(the steam having been let into the steam-cham-
ber a to heat the cylinder,) the cutter to cut
tobacco, the fans and cylinder to revolve, and
the sieve to shake, the fan B sucks the cut to-
bacco away from the cutter and blows it up-
ward through the pipe C into the receiver D,
where the air is allowed to escape through the
sieve sides or windows, while the tobacco falls
into the mouth of the feed-pipe E, down which
it passes of its own gravity, through the head
F, into the cylinder H, and the cylinder being
heated and revolving the tobacco is dried
therein. The shelves e, as they revolve with
the cylinder, (if used,) catch up the tobacco,
carry it upward until it pours off down upon
the bottom of the cylinder, and meanwhile, by
the inclination of the cylinder, the tobacco is
gradually worked along from the upper end of
the cylinder to the lower end, where it is dis-
charged through the opening f in the head G,
and, if necessary to be screened, falls into the
sieve R, where it is sifted, those particles small

enough passing through the sieve into the box
or receptacle S, while the balance pass out over
the tail of the sieve, which is open at one end 70
and slightly inclined lengthwise for that pur-
pose. While the tobacco is passing through
the cylinder H it is exposed to a counter-cur-
rent of air, created by the fan L sucking air in
through the discharge-opening f, upward and 75
through the cylinder, out of it through the pipe
K, into the fan L, whence it is blown away
through the pipe M. The force or speed of
this current of air can be varied and controlled
by dampers in the pipe K, or by varying the 80
speed of the fan L, or by any other ordinary
devices.

It will be readily seen that for other pur-
poses the cutter will be dispensed with, while
the fan B and pipe C can be retained for ele- 85
vating the material to be dried; and, also, that
in place of the pipe C an ordinary bucket-ele-
vator can be used; and, further, that a hopper
can be attached to or put upon the upper part
of the feed-pipe when desired. 90

Referring to the means for supporting and
operating the drying-cylinder, it is important
that the rollers l l' serve as driving-rollers, and
for this purpose they are connected by a shaft,
l', operated by a bevel-gear, v w, just beneath 95
the cylinder, whereby it is driven by friction
due to its weight, and thus avoids all strain and
undue wear of the cylinder upon the fixed heads,
and at the joint-connections of the steam-inlet
and discharge-pipe h h' i' i, carried by said 100
heads.

It is also important that the flanges d of the
fixed heads should form a close lap joining
with the cylinder-rims o by inward-projecting
lips fitting over said rims. 105

Referring to Fig. 6, the joint-connections of
the steam inlet and discharge pipes are shown
as formed by packing x, interposed between
the fixed pipes h i and the revolving pipes h'
and i', the said fixed pipes telescoping with
the revolving pipes at the cylinder-heads, and
being of a sufficiently less diameter than the
interior of the revolving pipes to allow said
packing x to be placed between them. The
packing is compressed to make the joint steam-
tight by being pressed by a collar, z', on the 110
fixed pipe against an interior collar, z, of the
revolving pipe, the said collar z' being forced
inward by screws x² in a collar, z², on the end
of the pipe h' outside of the cylinder-head. 115
120

What I claim as my invention, and desire
to secure by Letters Patent, is—

1. The revolving drying-cylinder enveloped
by a circumferential steam-space, a, formed by
the cylinder c proper and jacket or shell b, in
combination with fixed heads, the steam-inlet
pipe h h', and the steam and water discharge
pipe i' i, the said pipes having each an interior
section revolving with the cylinder and con-
nected with a fixed section by a joint, substan- 125
tially as described, for the purpose specified.

2. The combination of a revolving cylinder
enveloped by a circumferential steam-space, a,
with the fixed heads F and G, the steam inlet

and discharge pipes communicating with said steam-space, and a water-discharging device within the said steam-space, whereby to gather, lift, and discharge the water through the steam-outlet pipe as the cylinder revolves.

5 3. The combination of the fixed heads F and G, having the overlapping and inwardly-projecting flanges *d*, with the cylinder H, having the circumferential end rims, *o o*, with which the flanges lap, substantially as described, for the purpose specified.

10 4. The combination of a cylinder, adapted to be revolved within fixed heads, with the automatic feed device, consisting of the cutter and the forcing-fan A B, the pipe C, a closed hopper, into which said pipe C discharges, having provision for the escape of the air from said forcing-fan, and the pipe E, connecting said closed hopper with the fixed head G of said revolving cylinder, substantially as described.

15 5. The combination, in a drier, of a cylinder enveloped by a circumferential steam-space, *a*, and adapted to be revolved within fixed heads, having steam inlet and discharge pipes communicating with said steam-space, with the fan B for blowing the material into the feed-hopper D, and the exhauster L for drawing cold air through the drying-cylinder, substantially as described.

20 6. The combination, in a drier, of the revolv-

ing cylinder H, provided with the supporting-rollers *l l' m m*, the rollers *l l'* being mounted upon a driving-shaft and serving to drive the cylinder by friction, thereby relieving the cylinder of all strain and unequal wear upon its 35 joint-connections, with the fixed heads and the steam inlet and discharge connections, substantially as described.

7. In a tobacco-drier, the combination of the double-shell cylinder H, fixed heads F and G, 40 the steam-inlet pipe *h h'*, and the water and steam discharge pipe *i' i*, the exhaust-fan L, connected with the cylinder-head, the cutter A, fan B, spout C, the receiver D, the feed-pipe E, and the discharge-opening *f*, constructed and 45 operating substantially as described, for the purpose set forth.

8. In a tobacco-drier, the combination of the cylinder H, stationary heads F G, steam-pipes *h i*, exhaust-fan L, and pipe K, with the cutter 50 A, fan B, elevating-spout C, receiver D, feed-pipe E, discharge-opening *f*, and sieve R, constructed and operating together substantially as and for the purpose set forth.

In witness whereof I have hereunto set my 55 hand this 10th day of March, 1881.

ANSON NEWTON PALMER.
